US0D1065115S

(12) **United States Design Patent** (10) Patent No.: **US D1,065,115 S**
(45) Date of Patent: ** *Mar. 4, 2025

(54) **KEYPAD**

(71) Applicant: **Lutron Technology Company LLC**,
Coopersburg, PA (US)

(72) Inventors: **Gregory Altonen**, Easton, PA (US);
Jason C. Killo, Emmaus, PA (US);
Matthew Philip McDonald,
Phoenixville, PA (US); **Sean Tucker**,
Bethlehem, PA (US)

(73) Assignee: **Lutron Technology Company LLC**,
Coopersburg, PA (US)

(*) Notice: This patent is subject to a terminal disclaimer.

(**) Term: **15 Years**

(21) Appl. No.: **29/916,494**

(22) Filed: **Nov. 13, 2023**

Related U.S. Application Data

(63) Continuation of application No. 29/863,533, filed on Dec. 20, 2022, which is a continuation of application No. 29/825,536, filed on Feb. 2, 2022, now Pat. No. Des. 977,439, which is a continuation of application No. 29/823,705, filed on Jan. 19, 2022, now Pat. No. Des. 976,845, which is a continuation of application No. 29/653,545, filed on Jun. 15, 2018, now Pat. No. Des. 941,783.

(57) **CLAIM**

The ornamental design for a keypad as shown and described.

DESCRIPTION

FIG. 1 is a front perspective view of a keypad showing our new design;
 FIG. 2 is a front view thereof;
 FIG. 3 is a left side view thereof;
 FIG. 4 is a right side view thereof;
 FIG. 5 is a top view thereof;
 FIG. 6 is a bottom view thereof;
 FIG. 7 is an enlarged view of a button of FIG. 1;
 FIG. 8 is an enlarged view of a button of FIG. 2;
 FIG. 9 is an enlarged view of a button of FIG. 4;
 FIG. 10 is an enlarged partial view of the faceplate of FIG. 1;
 FIG. 11 is an enlarged partial view of the faceplate of FIG. 2;
 FIG. 12 is an enlarged view of the faceplate of FIG. 4;
 FIG. 13 is an enlarged view of the faceplate of FIG. 6;
 FIG. 14 is a front perspective view of a second embodiment thereof;
 FIG. 15 is a front view thereof;
 FIG. 16 is a left side view thereof;
 FIG. 17 is a right side view thereof;
 FIG. 18 is a top view thereof;
 FIG. 19 is a bottom view thereof;
 FIG. 20 is an enlarged view of a button of FIG. 14; and,
 FIG. 21 is an enlarged view of a button of FIG. 15.
 The uniform dashed broken lines illustrate structure or features which form no part of the claimed design.
 CAD lines in the drawings illustrate contour and not surface ornamentation.
 In FIGS. 7-13 and FIGS. 20-21, the broken lines identify enlargements.
 In FIGS. 14-21, grayscale shading illustrates contrast in appearance. In FIGS. 14-21, the dark shading illustrates the appearance of a matte surface. In FIGS. 14-21, the light shading illustrates the appearance of a reflective/shiny surface. In FIGS. 14-21, the unshaded portions are claimed without regard to surface finish.
